(57) **CLAIM**

We claim the ornamental design for a food package, as shown and described.

DESCRIPTION

FIG. 1 is a perspective view of a first embodiment of a food package of our new design;

FIG. 2 is a top plan view of the food package of FIG. 1;

FIG. 3 is a bottom plan view of the food package of FIG. 1; FIG. 4 is a right side elevational view of the food package of FIG. 1;

FIG. 5 is a left side elevational view of the food package of FIG. 1;

FIG. 6 is a back side elevational view of the food package of FIG. 1;

FIG. 7 is a front side elevational view of the food package of FIG. 1;

FIG. 8 is a perspective view of a second embodiment of a food package of our new design;

FIG. 9 is a top plan view of the food package of FIG. 8;

FIG. 10 is a bottom plan view of the food package of FIG. 8; FIG. 11 is a right side elevational view of the food package of FIG. 8;

FIG. 12 is a left side elevational view of the food package of FIG. 8;

FIG. 13 is a back side elevational view of the food package of FIG. 8; and,

FIG. 14 is a front side elevational view of the food package of FIG. 8.

Portions of the food package shown in broken lines in the figures are for illustrative purposes only and form no part of the claimed design.
